(57) **CLAIM**

The ornamental design for an enclosure for lift control, as shown and described.

DESCRIPTION

FIG. 1 is a front perspective view of the enclosure for lift control of the present invention looking at the front and left side;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a rear elevational view thereof.

The broken lines immediately adjacent the shaded areas represent the bounds of the claim and all other broken lines are for illustrative purposes only. None of the broken lines form a part of the claimed design.
